Primary Examiner — Sandra Snapp*Assistant Examiner* — Anehita E. Oribabor(74) *Attorney, Agent, or Firm* — JEEN IP LAW, LLC(57) **CLAIM**

The ornamental design for a data transmission cable, as shown and described.

DESCRIPTION

FIG. 1 is a front, right and bottom perspective view of a data transmission cable, showing my new design;

FIG. 2 is a front view thereof;

FIG. 3 is a rear view thereof;

FIG. 4 is a left side view thereof;

FIG. 5 is a right side view thereof;

FIG. 6 is an enlarged top plan view thereof; and,

FIG. 7 is an enlarged bottom plan view thereof.

The broken lines shown in the drawings illustrate portions of the data transmission cable that form no part of the claimed design.

1 Claim, 7 Drawing Sheets(56)
